PRINTING TELEGRAPH APPARATUS

Filed Oct. 22, 1947

UNITED STATES PATENT OFFICE

2,572,075

PRINTING TELEGRAPH APPARATUS

Alfred Edward Thompson, Croydon, England, assignor to Creed and Company Limited, Croydon, England, a British company

Application October 22, 1947, Serial No. 781,370
In Great Britain October 24, 1946

6 Claims. (Cl. 178—27)

1

This invention relates to printing telegraph apparatus and more particularly to means to be provided for enabling the records of a received message to be readily distinguishable from a copy of a transmitted message.

It has previously been proposed to use a two-colour typewriter ribbon associated with positioning mechanism under the control of the keyboard, in such manner that all incoming messages are printed in black and all local record copy is printed in red.

It is the object of the present invention to avoid the need for using a special two-colour typewriter ribbon and to reduce to a minimum the mechanism involved in providing the desired facility.

According to the present invention printing telegraph apparatus comprises a keyboard, a transmitter controlled by said keyboard, a page printing telegraph receiver, means for associating said receiver either to receive and print messages from a distant station or to print a local record of messages under control of said transmitter and means for causing a mark of identification to be printed automatically in the margin of all messages of one kind of message to distinguish such messages from the other kind.

For example, a vertical line, slightly longer than the height of the normal type, may be printed alongside each line of the message of all local record copy. The appearance of a continuous line extending from top of bottom of the margin of all local record copy is thus produced.

One embodiment of the invention will now be described in conjunction with the accompanying drawing, in which:

Fig. 1 shows the mark identification apparatus in printing position, and

Fig. 2 shows a portion of the mark identification apparatus in non-printing position.

The accompanying drawing shows a sufficient part of the mechanism of a page printing telegraph receiver and an associated transmitter to enable the invention to be understood. As shown in Fig. 1, the cam shaft of the transmitter carries a cam 1 which actuates a two-armed lever 2 for each rotation. The cam shaft is released for rotation under control of a keyboard (not shown), for each signal to be transmitted, in any well-known manner. The keyboard transmitter is associated with a receiver of the kind comprising a stationary platen and a moving typewheel chariot. Means are provided whereby in well-known manner the receiver is connected to receive messages from a distant station, or operates to print a local record of messages under control of said transmitter. An interposing member 3 having a marking face 3A, is disposed alongside the beginning-of-line position of the typewheel

2

chariot and is mounted to slide vertically in guide member 10 and is normally held by spring 4 with its upper end lower than the ink-ribbon 5 by means of which characters are printed on a sheet of paper carried by a platen 6 mounted in a stationary part of the machine.

The interposing member 3 carries a lever 7 urged by a spring 8 to rotate counter-clockwise. The typewheel chariot 9a carries a projection 9, 10 which, when the chariot is in beginning-of-line position, pushes lever 7 into a position to be engaged by lever 2, as shown in the drawing. In this position, therefore, the cam 1 if set into rotation under control of the keyboard acts on 15 lever 2 which in turn acts on lever 7 to lift interposing member 3 into the position shown in the drawing. In this position it is temporarily held by a stop on the member 3 engaging a member 10A, which may be the upper end of the guide 10 20 in which interposing member 3 slides. The upper end of the member 3 is then opposite the ink ribbon 5 and also the end of a lever 11 actuated by the printing cam in the receiver.

Keys 13 are representative of a full set of keys 25 making up a keyboard of a printing telegraph transmitter. Universal bar 14 is adapted to be moved against the tension of spring 14a upon the depression of any of the keys 13. Pivot member 15 is adapted to be moved in a clockwise direction 30 upon movement of bar 14.

Pivot member 15 actuates clutch controller 16 via the arm 17 which connects the pivot member and the clutch controller. Clutch mechanism 18 under control of the controller 16 causes the motor shaft 19 to rotate the cam sleeve 19a when 35 any key 13 is depressed. Cam 1 is carried upon cam sleeve 19a. Cam 20 is similarly mounted upon cam sleeve 19a and contains a "cylinder" cam 20.

Cylinder cam 20 is similarly mounted upon cam sleeve 19a and imparts to driving member 21 motion which is perpendicular to the plane of the motion of the cam sleeve, by means of cam follower 22 attached to driving member 21 at one end and actuated by the continuous curved groove 23 in the cam 20. The hump on cam 1 coincides with the maximum curve of the groove 23 in cam 20. Driving member is pivotally attached to one end of printing lever 11 and causes lever 11 to strike interposing member 3 when cam follower 22 travels in a right-hand direction by reason of the motion derived from said cam groove.

When the printing cam is actuated, lever 11 55 strikes the upper end of interposing member 3 to print a vertical line on the paper alongside the beginning of a line of typed characters. When member 3 is struck by lever 11 it is moved

clear of member 10 but is held in position to strike the ink ribbon 5 against the paper on platen 6 by a step 12 under which the end of lever 11 engages. When lever 11 is withdrawn the interposing member 3 is lowered by its spring 4. The typewheel chariot is moved one step to the right in the drawing and the movement of projection 9 away from lever 1 allows that lever to be moved counter-clockwise to remove its end from contact with lever 2. Fig. 2 shows interposing member 3 in the unoperated position and with the typewheel chariot 9a moved out of beginning-of-line position. On subsequent actuations of lever 2 by cam 1 the interposing member 3 will be unaffected, until the typewheel chariot again returns to beginning-of-line position when a vertical line on the paper will again be printed.

When the receiver is actuated by a received message cam 1 will be stationary and interposing member 3 will not be moved at all. Thus the vertical line will only be printed for a home record of transmitted messages.

As stated above the vertical line printed is preferably of such length that the lines printed extend continuously from top to bottom of the margin.

What is claimed is:

1. A page printing telegraph apparatus adapted to print messages received from a distant station and to print a local record of messages transmitted to a distant station by said apparatus, comprising a platen around which a message blank is adapted to be placed, means for causing a mark of larger dimensions than the size of the printing type of said apparatus to be printed in the margin of said message blank to identify all messages of one kind, a movable typewheel chariot adapted to move in a plane parallel to the axis of said platen, a type hammer adapted to strike said marking means under control of said apparatus and adapted to operate adjacent each line of printing of such messages of one kind.

2. A page printing telegraph apparatus as claimed in claim 1, wherein said marking means comprises a vertical type member having a type face equal to the combined height of the printing type of said apparatus and the space between printed lines, whereby there is produced on all messages of one kind a continuous line extending from top to bottom of the margin thereof.

3. A page printing telegraph apparatus as claimed in claim 1, wherein said means for selectively actuating said marking means comprises a movable typewheel chariot, adapted to move in a plane parallel to the axis of said platen, a cam operated by said apparatus, means for transmitting movement of said cam to said marking means to raise same to a printing position, a lever attached to said marking means and adapted to selectively engage said transmission means, means attached to said chariot for engaging said lever with said transmission means upon return of said chariot to the beginning-of-line position, a type hammer adapted to strike said marking means, said hammer under control of said apparatus.

4. A page printing apparatus adapted to print messages received from a distant station and to print a local record of messages transmitted to a distant station by said apparatus, comprising a platen around which a message blank is adapted to be placed, a movable typewheel chariot adapted to move in a plane parallel to the axis of said platen, a cam shaft carrying a cam thereon in said apparatus, means for rotating said cam shaft one revolution for each signal transmitted

by said apparatus, a movable, vertical type member located near one extremity of said platen beyond the line of travel of said chariot, said member having a type face equal to the combined height of the printing type of said apparatus and the space between printed lines, means for transmitting movement of said cam to said member to raise same to printing position, a lever attached to said member and adapted to selectively engage said transmission means, spring means for normally urging said lever out of engagement with said transmission means, means attached to said chariot for engaging said lever with said transmission means upon return of said chariot to the beginning-of-line position thereof, means for holding said type member in printing position, a type hammer adapted to strike said type member, means in said apparatus for actuating said hammer, means operative during the actuation of said hammer for disengaging said type member from said holding means, whereby there is produced on all messages transmitted by said apparatus a continuous line extending from top of bottom of the margin thereof.

5. A page printing telegraph apparatus adapted to print messages from a distant station and to print a local record of messages transmitted to a distant station by said apparatus, comprising a platen around which a message blank is adapted to be placed, means for causing a mark of larger dimensions than the size of the printing type of said apparatus to be printed in the margin of said message blank to identify all messages of one kind, a movable typewheel chariot adapted to move in a plane parallel to the axis of said platen, a type hammer adapted to strike said marking means under control of said apparatus, a cam operated by said apparatus, means for transmitting movement of said cam to said marking means to raise same to a printing position, means for holding said marking means in position to be struck by said type hammer after said marking means has been raised into printing position, a lever attached to said marking means and adapted to selectively engage said transmission means, means attached to said chariot for engaging said lever with said transmission means upon return of said chariot to the beginning-of-line position.

6. A page printing telegraph apparatus as claimed in claim 5, wherein said means for holding said marking means in position to be struck includes a first step and a second step on said marking means, said second step spaced from said first step, a fixed edge member engaging said first step when said marking means is not in a raised position, said fixed edge member adapted to engage said second step when said marking means is in a raised position, said marking means adapted to be released from engagement of said fixed edge member with said second step upon being struck by said type hammer.

ALFRED EDWARD THOMPSON.
